(75) Inventor: **Taizo Matsuda**, Tokyo (JP)

(57) **CLAIM**

(73) Assignee: **Nohmi Bosai, Ltd.**, Tokyo (JP)

The ornamental design for plate for a fire alarm repeater box, as shown and described.

(**) Term: **14 Years**

(21) Appl. No.: **29/111,503**

DESCRIPTION

(22) Filed: **Sep. 29, 1999**

FIG. 1 is a front view of a plate for a fire alarm repeater box, showing our new design;

(30) **Foreign Application Priority Data**

FIG. 2 is a rear view thereof;

Mar. 29, 1999 (JP) 11-7559

FIG. 3 is a top plan view thereof;

(51) **LOC (7) Cl.** **10-05**

FIG. 4 is a bottom plan view thereof;

(52) **U.S. Cl.** **D10/106**

FIG. 5 is a left side view thereof;

(58) **Field of Search** D10/104, 106,

FIG. 6 is a right side view thereof;

D10/121, 116; 340/815.01, 815.06, 815.11,

FIG. 7 is a cross-sectional view thereof, taken along line 7—7 in FIG. 1;

815.15, 815.16, 815.17, 815.21, 571, 572,

FIG. 8 is a cross-sectional view thereof, taken along line 8—8 in FIG. 1;

573, 627, 628, 629, 630

FIG. 9 is a cross-sectional view thereof, taken along line 9—9 in FIG. 1; and,

(56) **References Cited**

FIG. 10 is a perspective view thereof as viewed from front, right side and top.
